UNITED STATES PATENT OFFICE

2,459,887

BASEBALL GLOVE

Harry B. Latina, East St. Louis, Ill., assignor to
 Rawlings Manufacturing Company, St. Louis,
 Mo., a corporation of Missouri

Application October 7, 1946, Serial No. 701,661

10 Claims. (Cl. 2-19)

1

This invention relates to gloves for use in playing baseball, and more particularly to catcher's mitts of the kind shown in my Patent No. 2,288,467, wherein the thumb side of the ball receiving pocket is defined by an interior curb pad whose cross-sectional shape may be changed to vary the shape, size and/or location of said pocket by means of an adjustable lacing.

In the patent, the lacing extends through the palm cover into the ball receiving pocket and detracts from the appearance of the mitt and is liable to become worn and broken in service, the lace holes in the pocket are liable to elongate and tear, and the lacing causes discomfort to the hand used in pounding the pocket.

The principal object of the present invention is to overcome the above objections by providing the palm cover with a marginal extension that is folded therebeneath and around the curb pad and is secured thereto by lacing that is covered by said palm cover around the portion of the pocket defined by said curb pad. The invention consists in the baseball glove construction and in the combinations and arrangements of parts hereinafter described and claimed.

In the accompanying drawings, which form part of this specification and wherein like symbols refer to like parts wherever they occur,

Fig. 1 is a view looking at the palm side of a catcher's mitt embodying my invention.

Fig. 2 is a side elevational view of the front portion of the thumb side of said mitt.

Fig. 3 is a cross-sectional view on the line 3-3 in Fig. 1.

Fig. 4 is a plan view of the blank from which the palm cover flap is formed.

Fig. 5 is a view of the palm unit of the mitt with the palm cover partially broken away to disclose the inner marginal portion of the palm cover flap.

Fig. 6 is an inside face view of the palm unit of the mitt.

Fig. 7 is an interior face view of the back unit of the mitt.

Fig. 8 is a plan view of the palm cover blank; and

Fig. 9 is a plan view of the back cover blank.

In the accompanying drawings, my invention is shown embodied in a catcher's mitt of the kind shown in my Patent No. 2,288,467. The mitt comprises a back unit A and a palm unit B, both notched as at 1 to form the thumb portion 2 of said mitt. The back unit A comprises a cover 3 of leather or other suitable material, a similarly shaped base pad 4 seated on the inner face of

said cover, a horseshoe-shaped pad 5 seated on said base pad and extending therearound from the thumb side of the notch 1 to the finger side thereof and having a beveled inner peripheral portion 6, and a two-ply curb pad 7 seated on said horseshoe-shaped pad and extending substantially half way therearound from the finger side of said notch to a point opposite the bottom thereof, and having a transversely rounded top. All of said pads are made of felt or other cushioning material and are adhesively secured together. All of said pads are also bound together by stitching 8 looped over the curb pad 7 and passing through the base pad 4 and the horseshoe-shaped pad 5.

The palm section B comprises a palm cover 9 of leather or other suitable material having a marginal flap or extension 10 that is sewed or otherwise permanently secured thereto and extends approximately half way therearound on the thumb side thereof from a point near the end of the thumb portion 2 of the mitt to a point opposite the bottom thumb forming notch 1 thereof. Located beneath the palm cover 9 of the palm unit is a two-ply curb pad 11 of felt or other cushioning material that extends around the thumb side thereof from the outer end of the thumb portion 2 of the mitt to a point opposite the base of the thumb forming notch 1 thereof and has a transversely curved top. The marginal flap or extension 10 of the palm cover 9 extends therebeneath and around the top, sides and rear end of the curb pad 11, and said curb pad is retained in the channel formed by said folded cover flap by means of a cross lacing 12 that passes beneath said curb pad and extends through holes or slits 13 in the exposed outer marginal portion of said flap and in the covered inner marginal portion thereof.

The preassembled back and palm units A and B are placed in register with the curb pad 11 of the palm unit seated on the corresponding side of the horseshoe-shaped pad 5 of the back unit in endwise abutting relation to the curb pad 7 thereof. In this position of the parts, the cover 9 of the palm unit B covers the curb pad 7 of the base unit A and the middle portion of said cover roughly conforms to the inner sides of the two curb pads 7 and 11, to the beveled inner margin of the horseshoe-shaped pad 5 and to the uncovered portion of the base pad 4, thereby forming a relatively deep ball receiving pocket 17 in the palm surface of the mitt. The thumb forming notch or crotch 1 of the mitt opens into the ball receiving pocket 17 and the two separate curb

pads 7 and 11 are disposed in mere endwise abutting relation in the region of the heel portion of the mitt, thereby permitting said pocket to close around a ball caught therein. The peripheral portions of the back and palm units A and B of the mitt are tightly drawn together in edgewise abutting relation by means of a lacing 18 which passes through eyelet holes 13 in the back cover 3 and eyelet holes 28 in the palm cover 9 and in the marginal flap or extension 10 thereof.

The hereinbefore described baseball glove construction has several important advantages. The curb pads 7 and 11 shape and support the sides of the ball receiving pocket 17; and the cross-sectional shape of the curb pad 11 of the palm unit B of the mitt may be easily changed to vary the size, shape and location of said pocket merely by tightening the cross lacing 12 that secures the curb 11 within the retaining flap 10 provided therefor on the palm cover 9 of said mitt. The marginal curb retaining flap 10 of the cover 9 of the palm unit B extends beneath said cover; and the lace holes 13 in the inner margin of said flap and the portions of the lacing 12 that extend through said holes are completely covered by said cover, thereby greatly improving the appearance of the palm side of the mitt and protecting the lacing from wear and preventing it from hurting the hand used in pounding the ball receiving pocket 17 into shape. This arrangement also relieves the ball receiving pocket forming portion of the palm cover 9 of strains heretofore imposed thereon by the curb tightening and shaping lacing.

Obviously, the hereinbefore described baseball glove construction admits of considerable modification. Therefore, I do not wish to be limited to the precise construction shown.

What I claim is:

1. A baseball glove comprising back and palm covers secured together around their peripheral portions, said palm cover having a ball receiving pocket, padding interposed between said covers and including a curb pad that shapes and supports a side portion of said pocket, and means extending between said covers and across said curb pad for changing the cross-sectional shape of said curb pad.

2. A baseball glove comprising back and palm covers secured together around their peripheral portions, said palm cover having a ball receiving pocket, padding interposed between said covers and including a curb pad that shapes and supports a side portion of said pocket, and means extending between said covers and across said curb pad and accessible from the side edge of said glove for changing the cross-sectional shape of said curb pad.

3. A baseball glove comprising back and palm covers secured together around their peripheral portions, said palm covering having a ball receiving pocket, padding interposed between said covers and including a curb pad that shapes and supports a side portion of said pocket, and means accessible from the side edge of said glove and entirely clear of said pocket for changing the cross-sectional shape of said curb pad, said means comprising a portion of said palm cover that extends over the outer side of said curb pad, beneath said palm cover, across said curb pad and over the inner side thereof, and a lacing extending across said curb pad and engaging said portion of said palm cover on said outer and inner sides of said curb pad.

4. A baseball glove comprising back and palm

covers secured together around their peripheral portions, said palm covering having a ball receiving pocket, padding interposed between said covers and including a curb pad that shapes and supports a side portion of said pocket, and means accessible from the side edge of said glove and entirely clear of said pocket for changing the cross-sectional shape of said curb pad, said means comprising a marginal extension of said palm cover having an exposed portion covering the outer side of said curb pad and a portion disposed beneath said palm cover and covering the palm cover opposing face of said curb pad and the inner side thereof, and a lacing extending across the back cover opposing face of said curb pad and through the portions of said marginal extension that cover said outer and inner sides of said curb pad.

5. The combination set forth in claim 2 wherein the means for changing the cross-sectional shape of the curb pad is secured to the palm cover independently of the back cover, whereby said palm cover and curb pad are attachable to said back cover as a complete preassembled unit.

6. A baseball glove comprising back and palm covers secured together around their peripheral portions, said palm cover having a ball receiving pocket, padding interposed between said covers and including two curb pads disposed in end to end relation at the heel of said glove and shaping and supporting the side portions of said pocket, and means extending between said covers and around at least one of said curb pads and accessible from the side edge of said glove for changing the cross-sectional shape of said curb pad.

7. A baseball glove comprising back and palm covers secured together around their peripheral portions, said palm covering having a ball receiving pocket, padding interposed between said covers and including two curb pads disposed in end to end relation at the heel of said glove and shaping and supporting the side portions of said pocket, and means accessible from the side edge of said glove and entirely clear of said pocket for changing the cross-sectional shape of at least one of said curb pads, said means comprising a marginal extension of said palm cover that extends over the outer side of said curb pad and beneath said palm cover and over the palm cover opposing face of said curb pad and the inner side thereof, and a lacing extending across the back cover opposing face of said curb pad and through the portions of said extension that extend over said inner and outer sides thereof.

8. A baseball glove comprising back and palm covers secured together around their peripheral portions, said palm cover having a ball receiving pocket, padding interposed between said covers and including two curb pads disposed in end to end relation at the heel of said glove and shaping and supporting the side portions of said pocket, and means accessible from the side edge of said glove and entirely clear of said pocket for changing the cross-sectional shape of at least one of said curb pads, said means comprising a member secured to the margin of said palm cover and having a portion extending outwardly thereof over the outer side of said curb pad and a portion extending inwardly beneath said palm cover and over the palm cover opposing face and inner side of said curb pad, and a lacing extending across the back cover opposing face of said curb pad and through the portions of said ex-

tension that extend over said inner and outer sides thereof.

9. A baseball glove comprising back and palm covers secured together around their peripheral portions, said palm cover having a ball receiving pocket, padding interposed between said covers and including a base pad seated against the inner face of said back cover, a horseshoe-shaped pad seated on said base pad and two curb pads seated on said horseshoe-shaped pad and extending on opposite sides thereof from its closed end to its open end and shaping and supporting the sides of said pocket and means extending between said covers and across at least one of said curb pads and accessible from the side edge of said glove 15 for changing the cross-sectional shape of said curb pad.

10. A baseball glove comprising back and palm covers secured together around their peripheral portions, said palm cover having a ball receiving pocket, padding interposed between said covers and including a base pad seated against the inner face of said back cover, a horseshoe-shaped pad seated on said base pad and two curb pads

seated on said horseshoe-shaped pad and extending on opposite sides thereof from its closed end to its open end and shaping and supporting the sides of said pocket and means accessible from the side edge of said glove and entirely clear of said pocket for changing the cross-sectional shape of at least one of said curb pads, said means comprising a marginal extension of said palm cover that extends over the outer side of said curb pad, beneath said palm cover and over the palm cover opposing face of said curb pad and over the inner side thereof, and a lacing extending across the back cover opposing face of said curb pad and through the portions of the extension that cover the inner and outer sides of said curb pad.
